BATTERY CHARGING DEVICE

Filed March 25, 1925

Henry S. Werner

INVENTOR

BY Victor J. Evans

ATTORNEY

WITNESS:

R. G. Wise

UNITED STATES PATENT OFFICE.

HENRY S. WERNER, OF MEMPHIS, TENNESSEE.

BATTERY-CHARGING DEVICE.

Application filed March 25, 1925. Serial No. 18,301.

- This invention relates to electrical devices, particularly to alternating current rectifiers, and has for its object the provision of a novel device or apparatus to rectify alternating current for charging storage batteries or the like, the invention including the employment of a rectifying bulb or thermionic diode having a burned out or broken filament.
- 10 An important object is to provide an apparatus of this character including arc means whereby the tube may be excited instead of by the usual heated filament.
- Another object is the provision of an apparatus of this character in which use is made of an auxiliary source of current such as one of the storage batteries on charge to energize means for producing a high tension current for exciting the bulb.
- 20 A further object of the invention is to provide an apparatus of this character in which the construction and arrangement are such that the exciting coil will not vibrate upon interruption of the current supply or 25 on account of the existence of bad interconnection of the batteries, the normal position of the contacts of the relay device being open.
- With the above and other objects and advantages in view, the invention consists in the details of construction and arrangement of parts to be hereinafter more fully described and claimed, and illustrated in the accompanying drawings, in which:
- 30 Figure 1 is a diagram of the system, and Figure 2 is a detail perspective view of the bulb equipped with an auxiliary member for applying current thereto.
- Referring to the drawings wherein is disclosed a preferred embodiment of the invention, the numeral 10 designates a rectifier bulb of a commercial type such for instance as the "Tungar" which bulb is really a thermionic diode inasmuch as it includes a 40 filament 11 and a plate or target 12. However, in the present instance it will be observed that the filament 11 is represented as burned out or broken as my invention contemplates the employment of such bulbs which under ordinary systems are thrown away as worthless. In carrying out the invention I provide a band or other metallic 45 conducting member 13 arranged in encir-
- cling relation to the bulb and having means 14 thereon for effecting connection of a conductor 15 therewith. The current used in connection with this bulb is the ordinary alternating current which may range from one hundred to one hundred and twenty-five volts and which may be of any frequency, say for instance from between thirty to five hundred cycles. I preferably employ a two pole single throw switch designated broadly by the numeral 16 for controlling connection of the entire apparatus to the power line which includes the conductors 17 and 18. These conductors 17 and 18 are connected respectively with contacts 19 and 20 of the switch structure, while connected with the opposite contacts 21 and 22 are conductors 23 and 24, the former of which is connected with the filament 11 and the latter of which is connected with a suitable rheostat 25 having a movable contact arm 26 leading to a double throw switch designated broadly by the numeral 27. An ammeter A may be interposed in the conductor 26 in order that the output from the tube may be readily ascertained at any time.
- The numeral 28 designates the storage batteries to be charged, and connected with the positive terminal of the battery or one endmost positive terminal of a series of batteries, in case more than one is being charged, which is probable, is a conductor 30 connected with one contact 31 of the switch 27, while connected with the negative terminal of the battery or batteries is a conductor 32 leading to the other contact 33 of the switch 27 and connected with the plate 12. This switch 27 includes a movable contact arm 34 adapted to be brought into engagement with either the contact 31 or the contact 33, as the case may be, as will be hereinafter explained.
- I also provide a starting relay indicated broadly by the numeral 35 and including a pair of electro-magnets 36 and 37 between which is positioned an armature 38 adapted to engage a contact 39. The plate or target 12 is connected by a wire 40 with one terminal of the winding of the electro-magnet 36 which has its other terminal connected by a wire 41 with the wire 23. The filament 11 is connected by a wire 42 with one terminal of the winding of the electro-mag-

net 37 which has its other terminal connected by a wire 43 with the wire 24. The contact 39 has connected therewith a wire 44 connected with the wire 40.

5 In order that a spark may be produced across the gap in the broken filament 11, I make use of a high tension transformer designated generally at 45 and including primary and secondary coils 46 and 47 respectively, both of which are connected by a wire 48 with the armature 38. The secondary coil 47 has its other terminal connected with a metallic member 49 which is spaced from a similar member 50 with which connects the conductor 15. The members 49 and 50 are spaced apart to define a spark gap 51. The remaining terminal of the primary coil 46 is connected with a vibrator 52 adapted to engage and disengage a contact 53 with which is connected a wire 54 connected with a six volt tap on the battery or batteries 28. A condenser 55 may be shunted across the vibrator in the usual manner to reduce sparking at the contact points.

10 In the operation of the device it will be seen that ordinarily the armature 48 is in a neutral position out of engagement with the contact 39. Assuming that the batteries 28 have been connected on the line, to start operations it is first necessary to close the switch 16 and to swing the arm 34 of the switch 27 into engagement with the contact 33. When this is done current flows from the wire 17 through the wires 23 and 41 to the electro-magnet 36, wire 40, wire 32, contact 33, arm 34, wire 26, rheostat 25, and wire 24 through the switch 16 and back through the wire 18. This causes energization of the electro-magnet 36 and the armature 38 will be attracted and brought into engagement with the contact 39. Current then flows from the six volt tap of the storage battery, through the wire 54, vibrator 52 and coil 46, wire 48, armature 38, contact 39, wire 44, and wires 40 and 32 back to the negative terminal of the storage battery, the circuit being thus complete. The high tension current induced in the secondary coil 47 will jump the gap 51 and pass through the wire 15 to the band 13, thus exciting the rectifying bulb 10. As soon as the bulb starts operating the switch arm 34 is swung out of engagement with the contact 33 and into engagement with the contact 31 whereupon the battery or batteries will be charged. When the bulb starts operating, produced by placing a high potential across the band 13 and the filament 11, the electro-magnet 37 becomes energized, drawing the armature 38 out of engagement with the contact 39, thus rendering the transformer inactive. As current flows constantly through the electro-magnet 36, it is obvious that the electro-magnet 37 must

be of greater strength in order to hold the armature 38 out of engagement with the contact 30.

In the event of failure of the rectified current through breakage of connections or looseness thereof, the vibrator structure will not re-operate until the switch arm 34 is again engaged with the contact 33.

15 From the foregoing description and a study of the drawings it will be apparent that I have thus provided a battery charging device easily capable of utilizing a tube having a burned out or broken filament. Furthermore, the device is able to work on any frequency of alternating current due to the fact that it does not involve the employment of a transformer. It is also clear that the device will operate on direct current by short circuiting the bulb so that it will become inactive. In actual practice I have discovered that the apparatus will produce a comparatively smooth output current in view of the fact that there is no filament excitation by alternating current. Another distinctive feature of advantage is that there is no "kick back" effect as in the case of machines using transformers and that there will be greater stability of operation throughout.

20 While I have shown and described the preferred embodiment of the invention, it should be understood that I reserve the right to make such changes in the form, construction and arrangement of parts as will not depart from the spirit of the invention or the scope of the subjoined claims.

25 Having thus described the invention, I claim:

1. In a rectifying device for alternating current, a thermionic diode tube of the plate and filament type having an exhausted filament, means for supplying alternating current to the filament and plate, separately energized high tension means for producing an arc within the tube to effect excitation thereof, and means in circuit with and energized by current passing through the tube for automatically cutting out said high tension means upon excitation of the tube, said means including electro-magnets and a movable relay switch controlled thereby, one magnet being in circuit with the input to the diode and the other being in circuit with the output therefrom.

30 2. In a battery charging apparatus embodying a two element rectifying tube in which the filament is broken or burned out, input and output circuits connected with the tube, and means connected with the input circuit and located exteriorly upon the tube for effecting ionization and starting current flow between the filament and plate.

3. In a battery charging apparatus embodying a two element rectifying tube in which the filament is broken or burned out,

input and output circuits connected with the tube, and means connected with the input circuit and located exteriorly upon the tube for effecting ionization and starting current flow between the filament and plate, said means comprising a capacity element.

4. In a battery charging apparatus embodying a two element rectifying tube in which the filament is broken or burned out, input and output circuits connected with the tube, and means connected with the in-

put circuit and located exteriorly upon the tube for effecting ionization and starting current flow between the filament and plate, said means comprising a metallic member 15 extending around the outside of the tube and connected with a high tension current independent of said input circuit.

In testimony whereof I affix my signature.

HENRY S. WERNER.
